UNITED STATES PATENT OFFICE.

WILLIAM H. JORDAN, OF BROOKLYN, NEW YORK.

PAPER-RULING MACHINE.

SPECIFICATION forming part of Letters Patent No. 709,225, dated September 16, 1902.

Application filed May 10, 1902. Serial No. 106,758. (No model.)

To all whom it may concern:

Be it known that I, WILLIAM H. JORDAN, a citizen of the United States, residing in the borough of Brooklyn, city of New York, in the county of Kings and State of New York, have invented a certain new and useful Improvement in Paper-Ruling Machines, of which the following is a specification.

The main object of my invention is to provide a ruling-machine with a laterally-reciprocating pen-beam carrying a large number of closely-disposed pen-points for producing close wave or zigzag lines on paper sheets intended for checks, drafts, notes, stock certificates, and other papers representing financial transactions and which paper so ruled has become known in the trade as "safety-paper," the printing of the check, draft, &c., being done either before or after the safety-ruling.

In carrying my invention into effect I employ the usual pen-beam, which is provided with ordinary bearing-pins at each end, one pin being arranged to slide in an adjustable bearing and the other end being secured in a bearing connected with a reciprocating mechanism, which forms one of the main features of my invention. This reciprocating bearing or support is connected with an eccentric, which imparts the reciprocating motion and which may be driven at various speeds. I also provide improved means for feeding the paper sheets in a machine of this character; also, a heating device for hastening the drying of the ink, and a device for dropping the inked sheets to the strings or belt, which carries the sheets to the lay-boy without turning them over in the transfer from one carrier to the other. I also provide other novel devices and combinations of devices, which will be hereinafter more fully described, and pointed out in the claims.

My invention is illustrated in the accompanying drawings, in which—

Figure 1 is a plan view of the machine; Fig. 2, a vertical central section; Fig. 3, an enlarged plan view of part of the pen-beam, the reciprocating bearing or support, and the operating mechanism therefor. Figs. 4 and 5 are side elevations of the parts shown in Fig. 3 looking from opposite sides; Fig. 6, an enlarged vertical section of the reciprocating

device, taken on the line 6 6 of Figs. 3, 4, and 5; Fig. 7, an enlarged elevation of the reciprocating bearing for the pen-beam; Fig. 8, a vertical section on the line 8 8 of Figs. 3, 4, and 5; Figs. 9 and 10, side and end elevations, respectively, of the adjustable stationary bearing for the pen-beam; Fig. 11, a plan view illustrating two pen-beams adapted to reciprocate in the same direction or in opposite directions. Figs. 12 and 13 represent diagrammatically the wave or chain lines that may be produced by the arrangement of Fig. 11, and Fig. 14 a similar view showing a wave-line made with a very broad pointed pen or with a piece of fabric.

Referring to the drawings, A represents the usual belt for carrying the paper sheets to be ruled. This belt travels over rollers a, a' , a^2 , and a^3 , the mode of operation and function of which is the same as in straight-line ruling-machines.

B is the feed-roller, and b and b' are auxiliary feed-rollers, which serve to hold the paper flat and insure the feeding of the paper under the pens, roller b' being preferably as close to the pen-beam as possible. To further insure the paper sheets being fed under the pens, I provide an inclined guide b^2 , supported from the side rails of the frame under the pen-beam. If the forward end of a paper sheet curls upward after passing under feed-roll b' , guide b^2 will direct the same downward into contact with the belt, so as to cause the sheet to feed flat, and thus prevent curling up under the pen-beam. In this machine the usual feed-strings b^3 (shown in dotted lines) may be employed with some classes of work. Roll B is driven in pinion c , the shaft of which is driven by loose pulley C through the ratchet-clutch C', which is splined on the shaft. Feed-roll B is geared to roll a by gear b^4 , and roll a drives belt A, which in traveling over and under roll a' in contact therewith rotates the same. A pulley on the shaft of roll a^2 drives a pulley on the shaft of roll d , which drives feed-strings D around rolls d' and d^2 . Feed-strings D receive the inked paper sheets from belt A and convey the same over heating-plate E, which is heated by gas-flames or otherwise. The heating-plate and gas-piping are suitably supported from the frame of the machine. If desired, a suitable

75

80

85

90

95

100

form of electric heater may be employed instead of a gas-heater. To guide the paper sheets from belt A to strings D, a guide-plate d^3 is provided between rolls a^2 and d^2 , which 5 plate is secured to the top side rails of the frame, as shown in Fig. 1. From feed-strings D the paper sheets are fed over guide-plates d^4 to the drop feed-strings F, which are carried by short rolls f, placed at an angle, as 10 shown, to leave a wide V-shaped opening for the paper to drop through as it sags in the middle and to produce a greater sag at the inner end. The widest part of the opening is adjacent to roll d. The object of having the 15 paper sag more at the inner end than at the outer or forward end is to prevent the forward end dropping first and being engaged by belt or strings G, which feed the sheets to the lay-boy H. It will be seen that if the forward 20 end of the sheet were to drop first the movement of belt G in the opposite direction would tend to push the sheet backward and prevent the forward feed. One pair of rolls f for the drop-strings are driven by a pulley 25 belted to the pulley on roll d, and the shafts of said rolls f are connected by knuckle or universal couplings, as shown. To adjust the dropping-point for the paper sheets and prevent feeding beyond the frame of the machine, I provide an adjustable stop f'. Belt G travels over rolls g and g', the former being driven by a belt from a pulley on roll a'. 30 The rolls above referred to are all suitably journaled in bearings mounted on or formed in the frame of the machine.

To insure the final forward feed of the sheets under the pens and also to grip the sheets and hold them against lateral displacement due to the lateral reciprocation of the pens, I provide laterally-adjustable feeding or gripping rollers I, three of which are shown, although more may be employed. These rollers are in contact with belt A over roll a' and directly on the line of contact of the 45 pens. They are sleeved on a rod i and are held in the adjusted positions by set-screws or by other suitable means. Rod i is journaled in sliding blocks i', placed in slots in the standards I², which are mounted on the 50 side rails of the machine-frame. These blocks are pressed downward by springs, so that rollers I will firmly engage the paper sheets.

The operation of the parts thus far described is as follows: The paper sheets are fed from the usual feed-table to feed-roll B, and auxiliary feed-rolls b and b' continue the forward feed under the pens. The feed or gripping rollers I continue the forward feed 55 and hold the sheets against lateral displacement after they pass clear of feed-roll b'. Belt A then carries the sheets along over guide d^3 and onto strings D, where the heat from the heating-plate E hastens the drying of the ink. Strings D carry the sheets over guide d^4 and onto drop-strings F, which feed the sheets forward until they strike stop f',

when the sagging of the sheets causes them to drop through upon belt or strings G. This belt carries the sheet back to the lay-boy H with the inked side upward. The ink on the sheets will practically be dry when they drop upon belt G, and the long travel back to the lay-boy and the passage under the heater will insure the complete drying of the ink. It 70 will be understood that in a machine of this character the paper sheets are fed forward much slower than in straight-line ruling-machines and that the speed may be varied according to the wave-line desired. 75

The means for imparting the lateral reciprocating motion to the pen-beam, which is shown in detail in Figs. 3 to 8, inclusive, will now be described. The pen-beam J is of the usual construction and is provided with the 80 usual pivot-pins. The reciprocating bearing of the pen-beam comprises a swivel 1, provided with a set-screw 2 for binding the pivot-pin of the pen-beam after the pens are adjusted with respect to the paper. This swivel 85 is mounted on a slide 3, which slides on a pin 4, projecting horizontally from an angular bracket or slide 5, working vertically on a pin 6, which projects downward from the reciprocating slide 7. Swivel 1 and slide 3 are 90 adjusted horizontally by an adjusting-screw 8, which is journaled in and held against longitudinal movement on slide 5 by means of screw 9, which is journaled in and held against longitudinal movement on slide 7, the free end of this screw working in a screw-threaded hole in slide 5. Slide 7 works horizontally in a 95 bearing 10, mounted on the side rail 11 of the machine-frame, and is connected by a pin or bolt with pitman 12, which is reciprocated by eccentric-pin 13. The pitman is held in place by a collar 14. A shank on the eccentric 13 is 100 inserted and clamped in the head 15 on a vertical spindle 16, which is journaled in a vertical bearing 17, made integral with bearing 10. At the lower end of spindle 16 is secured a miter spur-gear 18, which meshes with a 105 similar gear 19, secured to a pinion 20, the latter being keyed to or formed integral with a sleeve 21. This sleeve rotates on a rod 22, which is inserted in and clamped to a block 23, bolted to the under side of rail 11. Pinion 20 is driven by a train of gear-wheels 110 driven by gear-wheel 24 on the shaft driven by pulley C. To vary the length of the reciprocations of the pen-beam, and hence vary the wave-lines traced on the paper sheets, I 115 employ eccentrics 13 of different pitch—that is, the diameters are the same in each case, but the shanks which enter the socket 15 are placed at different points from the center. The speed of the eccentric, and hence the 120 number of reciprocations in a given time, may be varied by substituting gear-wheels of different diameters for gear-wheel 25, which meshes with pinion 20. This I accomplish 125

by providing pinion 26 with a reduced flange and spline adapted to receive gear-wheel 25. Pinion 26 is journaled on the reduced portion of rod 27, which is bolted in a slot in arm 28, which projects from block 23, the arc of said slot being struck from the center of the gear with which pinion 26 meshes. The object of the slotted arm 28 is to permit rod 27 to be shifted when a larger gear-wheel is substituted for gear-wheel 25 to properly mesh with pinion 20. Gear-wheel 25 and pinion 26 are held in place by a split washer 29 and nut 30. To remove gear-wheel 25, it is only necessary to loosen nut 30 and slip the washer off the rod, when the wheel can be slipped over the nut. The stationary adjustable bearing for the pen-beam is provided with means for horizontal and vertical adjustment similar to the reciprocating bearing. This bearing comprises two blocks 31, which are bolted on side rail 11^a and which are connected by a rod 32. These two blocks carry a horizontal feed-screw 33, and sliding on rod 32, by means of screw 33, is a slide-block 34. This block has mounted upon it a rod 35, carrying a head 36, and which has a vertical feed-screw 37. A block 38, fed by screw 37, slides on rod 35, and this block carries a swivel-block 39, on the under side of which is pivoted the bearing 40 for pivot-pin J² of the pen-beam. It will be noted that the distance between swivels 1 and 40 is greater than the length of the pen-beam. This is to allow for lateral adjustment of the pens relative to the paper sheets to be ruled and to afford sufficient clearance between swivel 40 and the adjacent end of the pen-beam to allow the latter to reciprocate. In adjusting the pen-beam pivot-pin J², which is quite long, is first inserted in swivel 40 and pivot-pin J¹ is inserted in swivel 1. After the pen-beam is adjusted laterally and vertically it is clamped in position by set-screw 2. The operation of the pen-beam is sufficiently clear from the description of its parts. In starting the machine the pen-beam is first adjusted, and then clutch C' is shifted to the position shown in the drawings, whereupon the feed-rolls, carrier-belt, and strings, and the pen-beam will be set in motion.

In Fig. 11 are shown two pen-beams J and J³, each provided with the reciprocating mechanism and bearings above described. The eccentric 13 may be set so that the beams reciprocate in opposite directions or in the same direction, or the eccentrics may be set so that one beam will have a slight lead over the other in the same direction, the effects of which will be apparent. In this arrangement the second pen-beam J³ may be driven by gearing meshing with the gearing for pen-beam J or by a belt driven by pulley C or by a train of gearing like that for beam J and provided with its own driving-pulley C. These being obvious arrangements, specific illustration thereof is omitted to avoid multiplicity of drawings.

Two of the effects that may be produced

by the arrangement of Fig. 11 are shown in Figs. 12 and 13. In producing the ruling of Fig. 12 the pens are closely disposed and the 70° wave-lines of the two sets intersect. In producing the ruling of Fig. 13 the pens are set farther apart and the pens of one beam are set to strike between the lines ruled by the pens of the other beam, the curves of each 75 approaching and receding.

In Fig. 14 are shown broad wave-lines, which may be produced by broad-pointed pens or by pieces of fabric carried by the pen-beam or by one or more ordinary pens. These 80 heavy wave-lines may also be ruled by a double beam, as in Fig. 11, the pens of each beam ruling alternate lines, or the pens may be arranged sufficiently wide apart to rule broad wave-lines, with the curves of adjacent 85 lines approaching and receding, as in Fig. 13. It will be evident that other effects may be produced by various forms of pens and by adjusting the speed of the reciprocating mechanism and the feed mechanism or by 90 adjusting the eccentrics to vary the relative reciprocations of the beams.

What I claim is—

1. In a ruling-machine the combination with a horizontal feeding-belt, of a reciprocating pen-beam for producing wave-lines, a heater for drying the ink, a horizontal conveyer in alinement with the feeding-belt receiving the inked sheets from the feeding-belt and carrying same over the heater, a lay-boy, and a second conveyer for delivering the paper sheets to the lay-boy, substantially as set forth.

2. In a ruling-machine, the combination with a horizontal feeding-belt, of a reciprocating pen-beam for producing wave-lines, a heater for drying the ink, a horizontal string conveyer in alinement with the feeding-belt receiving the inked sheets from the feeding-belt and carrying same over the heater, a lay-boy, and a second conveyer for delivering the paper sheets to the lay-boy, substantially as set forth.

3. In a ruling-machine, the combination with a feeding-belt, of a reciprocating pen-beam for producing wave-lines, a heater for drying the ink, a conveyer receiving the inked sheets from the feeding-belt and carrying same over the heater, a lay-boy, a second conveyer for delivering the paper sheets to the 120 lay-boy, and a transferring-conveyer for dropping the paper sheets from the first conveyer to the second conveyer with the inked sides upward, substantially as set forth.

4. In a ruling-machine, the combination with a feeding-belt, of a reciprocating pen-beam for producing wave-lines, a heater for drying the ink, a string conveyer receiving the inked sheets from the feeding-belt and carrying same over the heater, a lay-boy, a 130 second conveyer for delivering the paper sheets to the lay-boy, and a transferring-conveyer for dropping the paper sheets from the first conveyer to the second conveyer with

the inked sides upward, substantially as set forth.

5. In a ruling-machine, the combination with a feeding-belt, of a reciprocating pen-beam for producing wave-lines, a lay-boy for receiving the inked sheets, a conveyer for delivering said sheets to the lay-boy, and a transferring device for dropping the sheets to said conveyer with the inked sides upward, substantially as set forth.

6. In a ruling-machine, the combination with a feeding-belt, of a reciprocating pen-beam for producing wave-lines, a lay-boy for receiving the inked sheets, a conveyer for delivering said sheets to the lay-boy, and a transferring device consisting of a divided conveyer which allows the sheets to sag and drop through to the first-named conveyer with the inked sides upward, substantially as set forth.

7. In a ruling-machine, the combination with a feeding-belt, of a reciprocating pen-beam for producing wave-lines, a lay-boy for receiving the inked sheets, a conveyer for delivering said sheets to the lay-boy, and a transferring device consisting of two string conveyers set at an angle to each other and presenting a wide opening through which the sheets sag and drop to the first-named conveyer with the inked sides upward, substantially as set forth.

8. In a ruling-machine, the combination with a feeding-belt, of a reciprocating pen-beam for producing wave-lines, a heater for drying the ink, a conveyer receiving the inked sheets from the feeding-belt and carrying same over the heater, a lay-boy, a second conveyer for delivering the paper sheets to the lay-boy, and a transferring device consisting of a divided conveyer which allows the sheets to sag and drop through to the second conveyer, with the inked sides upward, substantially as set forth.

9. In a ruling-machine, the combination with a feeding-belt, of a reciprocating pen-beam for producing wave-lines, a heater for drying the ink, a conveyer receiving the inked sheets from the feeding-belt and carrying same over the heater, a lay-boy, a second conveyer for delivering the paper sheets to the lay-boy, and a transferring device consisting of two string conveyers set at an angle to each other and presenting a wide opening through which the sheets sag and drop to the first-named conveyer with the inked sides upward, substantially as set forth.

10. In a paper-ruling machine, the combination with the paper feeding and ruling mechanism, the lay-boy, and the conveyer for delivering the ruled sheets to the lay-boy, of a transferring device consisting of a divided conveyer which allows the sheets to sag and drop through to said conveyer with the ruled sides upward, substantially as set forth.

11. In a paper-ruling machine, the combination with the paper feeding and ruling mechanism, the lay-boy, and the conveyer for

delivering the ruled sheets to the lay-boy, of a transferring device consisting of two string conveyers set at an angle to each other and presenting a wide opening through which the sheets sag and drop to said conveyer with the ruled sides upward, substantially as set forth.

12. In a ruling-machine, the combination with several conveyers for the paper sheets, of a device for transferring the sheets from one conveyer to the other without turning the sheets over, consisting of two short conveyers separated so as to permit the sheets to sag in the middle and drop through, and an adjustable stop for checking the forward feed of the sheets on said conveyers, substantially as set forth.

13. In a ruling-machine, the combination with several conveyers for the paper sheets, of a device for transferring the sheets from one conveyer to the other without turning the sheets over, consisting of two short conveyers set at an angle to each other and presenting a wide opening so as to permit the sheets to sag in the middle and drop through, and an adjustable stop for checking the forward feed of the sheets on said conveyers, substantially as set forth.

14. In a ruling-machine, the combination with several conveyers for the paper sheets, of a device for transferring the sheets from one conveyer to the other without turning the sheets over, consisting of two short string conveyers traveling over two pairs of rollers set at an angle so as to present a V-shaped opening between them and permit the sheets to sag in the middle and to a greater extent at one end and drop through on a slant, and an adjustable stop for checking the forward feed of the sheets on said conveyer, substantially as set forth.

15. In a ruling-machine, the combination with the pen-beam, of a horizontally and vertically adjustable stationary bearing therefor at one end, a similarly-adjustable reciprocating bearing therefor at the other end, means for securing said pen-beam in its adjusted position both with respect to the paper to be ruled and to said reciprocating bearing, and means for imparting the reciprocating motion to said bearing, substantially as set forth.

16. In a ruling-machine, the combination with the pen-beam, of a horizontally and vertically adjustable stationary bearing therefor at one end, a similarly-adjustable reciprocating bearing therefor at the other end, means for securing said pen-beam in its adjusted position both with respect to the paper to be ruled and to said reciprocating bearing, an eccentric connected with said bearing, and a driving-gear for said eccentric whereby the reciprocating motion is imparted to said bearing, substantially as set forth.

17. In a ruling-machine, the combination with the paper-feeding mechanism and the conveyers, of two independently-reciprocating pen-beams for producing wave-lines, means for reciprocating said beams, and

means for independently adjusting the movements of said beams, substantially as set forth.

18. In a ruling-machine, the combination with the paper-feeding mechanism and the 5 conveyers, of two independently-reciprocating pen-beams for producing wave-lines, a stationary adjustable bearing for each of said beams, an adjustable reciprocating bearing for each beam, means for securing said beams 10 in their adjusted positions both with respect to the paper and to said reciprocating bearings, and means for imparting the reciprocating motion to said bearings, substantially as set forth.

19. In a ruling-machine, the combination, with the paper-feeding mechanism and the conveyers, of two independently-reciprocating pen-beams for producing wave-lines, a horizontally and vertically adjustable stationary bearing for each of said beams, a similarly-adjustable reciprocating bearing for each beam, means for securing said beams in their adjusted positions both with respect to the paper and to said reciprocating bearings, 25 and means for imparting the reciprocating motion to said bearings, substantially as set forth.

20. In a ruling-machine, the combination with the paper-feeding mechanism and the 30 conveyers, of two reciprocating pen-beams for producing wave-lines, a stationary bearing for each of said beams, a reciprocating bearing for each beam, means for securing said beams in their adjusted positions and to said reciprocating bearings, an eccentric connected with each of said reciprocating bearings, and driving mechanism for said eccentrications of said beams, substantially as set forth.

trics, whereby the reciprocating motion is imparted to said bearings, substantially as set forth.

21. In a ruling-machine, the combination with the paper-feeding mechanism and the conveyers, of two reciprocating pen-beams for producing wave-lines, an adjustable stationary bearing for each of said beams, an adjustable reciprocating bearing for each beam, means for securing said beams in their adjusted positions and to said reciprocating bearings, an eccentric connected with each of said reciprocating bearings, and driving mechanism for said eccentrics, whereby the reciprocating motion is imparted to said bearings, substantially as set forth.

22. In a ruling-machine, the combination with the paper-feeding mechanism and the 55 conveyers, of two reciprocating pen-beams for producing wave-lines, a stationary bearing for each of said beams, a reciprocating bearing for each beam, means for securing said beams in their adjusted positions and to said 60 reciprocating bearings, an eccentric connected with each of said reciprocating bearings, driving mechanism for said eccentrics, whereby the reciprocating motion is imparted to said bearings, and means for varying the reciprocations of said beams, substantially as set forth.

This specification signed and witnessed this 8th day of May, 1902.
